UNITED STATES PATENT OFFICE.

GUY MYERS HARTSOCK, OF DETROIT, MICHIGAN, ASSIGNOR TO STUDEBAKER CORPORATION, A CORPORATION OF NEW JERSEY.

GREASE GUN.

Application filed July 15, 1921. Serial No. 484,987.

To all whom it may concern:

Be it known that I, GUY MYERS HARTSOCK, a citizen of the United States of America, and resident of Detroit, in the county of Wayne and State of Michigan, have invented certain new and useful Improvements in Grease Guns, of which the following is a specification.

My invention relates to improvements in devices for introducing grease into cavities provided to accommodate the same, by means of pressure.

Heretofore it has been the practice to introduce the grease into these cavities by means of manually operated devices, such as a grease gun having a piston moved by a manually operated screw or like device. These devices when designed to give sufficient pressure were correspondingly slow in operation and the pressure was not evenly applied as it would vary inversely with the speed at which the plunger was operated; that is, the higher the pressure the slower the operation, and vice versa.

My invention minimizes this difficulty, if it does not entirely eliminate it, because the necessary pressure is obtained by a device operating on the principle of differential pistons, the larger piston being operated by fluid pressure, either thru the medium of a gaseous substance such as air or of a liquid such as water, the smaller piston acting on the grease to be delivered into the cavities, and forcing it into the same. By this arrangement it can readily be seen that by varying the pressure of the fluid on the larger piston, or by varying the ratios of the areas of the two pistons, or by varying both, any desired pressure can be obtained to force the grease into the cavities.

The overcoming of the relative slowness of operation, is perhaps a natural outcome of using a device operating on the principle of differential pistons, or at least this principle with its inherent construction offers a natural expedient in the solution of speeding up the operation of delivering the grease. Specifically, the speeding up of the delivery of grease depends upon the number of reciprocations of the piston acting on the grease in a given length of time. In this particular device passages lead from either side of the large piston to a two-way cock, controlling the admission of fluid pressure to either side of the piston and

the relieving of the pressure from the opposite side. This operation, the admission of pressure to one side of the piston and the relieving of pressure from the other side, is controlled by turning a two-way cock, an operation which under practical considerations takes no appreciable time. The action of the pistons, once pressure has been applied is much faster than any manually operated device and therefore the delivery of grease is much greater in comparison.

Having described the advantages of this invention, a more detailed description will follow, reference being had to the accompanying drawing which is a longitudinal section of a device embodying my present invention.

The main casing 1 is formed to provide a relatively large cylinder 2 in one end thereof and an axially extending sleeve 32 having a central opening communicating with the cylinder 2. A cap 33 forming a head for the open end of the cylinder 2 is secured thereto by bolts or other suitable means to form a unitary part thereof and has an axially extending sleeve 34 corresponding with the sleeve 32 but oppositely disposed in relation thereto. A piston 5 axially slidable in the sleeves 32 and 34 has threads formed thereon adjacent its mid-portion and receives thereon the main piston 3 which engages the cylinder 2 and is reciprocable therein. The sleeve 32 is interiorly threaded and receives therein the gland member 10 which is provided with a bore or cylinder 4 to slidably receive the right hand end of the piston 5 and has extending therefrom a hollow, corrugated nipple portion 35 which has an opening or passage 36 communicating with the bore or cylinder 4. A suitable packing 31 is provided at the inner end of the gland member 10 to seal the joint between the gland member 10 and the sleeve 32 and between the sleeve 32 and piston 5. A suitable lock nut 26 is screw-threaded on the gland member 10 to prevent the inadvertent turning or loosening of the same relative to the sleeve 32.

The sleeve 34 which is illustrated as integral with and extending from the cap 33 is also internally threaded and receives therein the gland member 11 which is similar to the gland member 10 and like the latter is provided with a bore or cylinder 37 which receives the left hand end of the piston 5.

for a purpose to be described later. A lock nut 26 is also screw-threaded on the gland member 11 to prevent rotation of the same relative to the casing 34. The gland member 11 is also provided with an extending nipple 38 exteriorly threaded to receive a flexible hose coupling (not shown) or for making a suitable connection with a member to be lubricated. The nipple 38 is provided with an axial opening 39, the outer end of which is of a larger diameter than the inner end which communicates with the cylinder opening 37. A suitable packing 31' is provided at the inner end of the gland member 11 for the same purpose as the packing 31 in the gland member 10.

The piston 5 is provided with an axial opening 19 which extends therethrough from end to end communicating with the cylinders 4 and 37. A ball 20 is positioned in the passage 19 adjacent its outlet or left hand end and is normally seated against a tapered flange forming a reduced portion thereof by a spring 27 which seats at its one end on the ball 20 and at its opposite end on the pin 27' secured in the piston 5 adjacent the mouth of the opening 19. The ball 20 forms a check valve which allows passage of grease thereby in one direction only, that is, from the cylinder 4 to the cylinder 37, but not vice versa.

To insure the passage of grease or other substances through the passage 19 into the cylinder 37 upon right hand movement of the pistons 3 and 5 and to prevent the grease from being forced back through the passage 36, a valvular means is provided in the passage 39 which will seal the passage and cause a vacuum in the cylinder 37 upon movement of the piston 5 to the right so that the grease in the cylinder 4 will be sucked through the passage 19 past the ball 20 and into the cylinder 37. The valvular means comprises a piston 12 reciprocable in the reduced portion 13 of the opening 39. This piston is provided with a longitudinal passage 17 extending from the rear or right hand face to a transverse passage 18 provided near the forward or left hand end thereof. A pin 15 forming a stop to limit the movement of the piston 12 is positioned in the reduced portion 13 of the passage 39 adjacent the cylinder 37 and a pin 14 positioned in the large portion of the passage 39 limits the movement of the piston 12 in its outward movement. A spring 16 interposed between the stop 14 and the piston 12 tends to push the piston 12 toward the stop 15 and the passage of grease past the piston 12 is normally prevented due to the fact that the walls of the reduced portion of the passage 39 cover or close the transverse opening 18 to the passage of the grease. Thus on the rearward or right hand movement of the pistons 3 and 5 a suction will be created

in the cylinder 37 which will cause the piston 12, assisted by the action of the spring 16, to follow the piston 5 until it abuts against the stop 15 and on the forward or left hand movement of the pistons 3 and 5 the piston 12 will be moved forward against the action of the spring 16. When the piston 5 is moved forwardly or to the left pushing grease before it, the grease is put under pressure which is transmitted to the piston 12 and when sufficient pressure is exerted thereon to overcome the action of the spring 16, the piston 12 will move forwardly to bring the transverse opening 18 therein past the end of the reduced portion of the passage 39, at which time the grease is free to flow through the passages 17, 18 and 39 to the grease cup or part to be lubricated.

The discharge ends of grease guns are usually connected to the grease cup or part to be lubricated by a flexible tube or other suitable means. As a considerable pressure is built up in the tube or connecting means, when grease is inserted therethrough, a certain amount of the grease will be extruded from the tube upon disconnecting the parts due either to the pressure, or, the tube having been previously expanded, to the corresponding contraction of the tube upon relieving the pressure therein. It will be apparent that if an ordinary check valve was substituted for the piston 12, it would be impossible to relieve such a pressure in the discharge connections because the check valve would seat immediately upon backward movement of the pistons 3 and 5. To relieve the pressure in the connections, the piston 12 is provided, which moves a limited distance with the piston 5 and thereby relieves the pressure above described. When the gun is discharging grease, the piston 12 will move forwardly to expose the transverse passage 18 therein to the enlarged portion of the passage 39 and will assume that position at the end of its discharge stroke, whether it be the full stroke of the piston 3 or only a part thereof and will assume that position when a quantity of grease has been received in the cylinder 37 and then pressure applied to force the same into the passage 39 to move the piston 12 forwardly against the compression spring 16. Upon backward movement of the pistons 3 and 5, a suction is created in the cylinder 37 which tends to draw or move the piston 12 with the piston 5 against the stop 15 which allows for expansion of the grease in the connecting tube and thereby relieves the pressure in the discharge connections so that upon disconnecting the same no grease will be exuded therefrom.

In order that no grease which may escape past the outside surface of the piston 5 and under the packing 31 or 31' may be carried into the main cylinder 2 and thereby ob-

struct the proper functioning of the device, relief spaces 46 are preferably provided in the casing 1 and the cap 33 around the piston 5 and between the cylinder 2 and the packing 31 and 31'. The relief spaces 46 are vented at 28 so that any grease passing the piston 5 will be trapped therein and delivered outside of the casing.

Secured to the upper part of the casing 1

10 is a valve casing 6 in which is rotatably mounted a valve 40 having an upwardly projecting stem 7 to which a handle 8 is non-rotatably secured to provide a means for rotating the valve 40. A gland 29 surrounding the stem 7 is screw-threaded into the casing 6 and a packing 30 is preferably inserted between the inner end of the gland 29 and the valve 40 to prevent leakage of air or liquid past the valve 40 and between the gland 29 and valve stem 7. The valve 40 is provided with two separate passages positioned perpendicular to the axis of the valve and in different planes, each of which comprises an opening 41 and a second opening 42 communicating therewith and radially disposed in relation thereto. The passages are identical with the exception that the lower openings are turned 90° about the axis of the valve 40 with respect to the upper openings. A vertically disposed blind passage 24 plugged at its open end is formed in the casing 6 and communicates with the passages formed in the valve 40 by cross passages 25 and 43 when the valve is turned 35 to bring its passages in mating relation therewith. A corrugated nipple 9 is screw-threaded into the casing 6 and is adapted to be connected with an air hose or other suitable device (not shown) whereby air under pressure can be delivered to the passage 24 through the axial passage 44 formed in the nipple 9. A horizontal passage 23 formed in the casings 1 and 6 extends from the valve 40 in the plane of the upper openings 41 and 45 42 to the cap 33 where it joins the passage 22 formed in the cap 33 which communicates with the cylinder 2 on the left hand side of the piston 3. A passage 45 in the casings 1 and 6 extends from the valve 40 in the plane of the lower openings 41 and 42 in said valve to the cylinder 2 on the right hand side of the piston 3.

Each radial opening 42 communicates with the respective passages 23 and 45 when brought in matching relation thereto and the openings 41 connecting with the passages 42 communicate with a passage, (not shown) leading to the atmosphere. As shown in the drawing, the valve 40 is positioned so that the lower passage 41 is in communication with the passages 25 and 45 and air under pressure is admitted to the cylinder 2 through the passages 44, 24, 25, 41 and 45 on the right hand side of the piston 3 to move the same to the left. At the

same time the upper passage 42 in the valve 40 is in communication with the passage 23 and the opening 41 connecting with the upper passage 42 is in direct communication with the atmosphere, thereby relieving any pressure at the left of the piston 3 in the cylinder 2 when the piston 3 is moved in that direction. It will be apparent that when the valve 40 is turned to bring the upper passage 41 into communication with the passages 43 and 23, air under pressure will be admitted therethrough and that the piston 3 will move from the left to right, at which time the port 41 connecting with the lower passage 42 will be in direct communication with the atmosphere to relieve pressure on that side of the piston 3. Thus, by turning the handle 8 which controls the valve 40, the pistons 3 and 5 will be moved to reciprocate when a suitable source of air or other liquid pressure is applied to the passage 44. It will also be apparent that if the nipple 35 is connected to a source of grease or other substances which it is desired to pump and when the pistons 3 and 5 move from the extreme right hand position to the extreme left hand position as shown in the drawing, the ball 20 will seat and a vacuum will be produced in the cylinder 4 which will cause the grease to be drawn into the cylinder 4 back of the piston 5. Upon reverse movement of the pistons 3 and 5, the ball 20 will be raised from its seat and the grease will flow from the passage 19 to the cylinder 37 from whence it will be forced through the passage 39 to the part to be lubricated upon the next left hand movement of the pistons 3 and 5.

Having described the detailed parts of the drawing and explained the construction of the device, it is thought that the operation of the same will be readily understood. The nipple 35 is preferably connected by a flexible tube to a source of grease supply, the nipple 38 is connected with the part to be lubricated, and the nipple 9 is connected to a source of fluid pressure such as air or water, but preferably air. Assuming that the piston 3 is at the right hand side of the cylinder 2 and the handle 8 turned to bring the lower passage 41 in the valve 40 into communication with the passages 25 and 45, it will be seen that air under pressure will be admitted to the right hand side of the piston 3 in the cylinder 2, which will move the same and the piston 5 to the left. As the ball 20 is normally seated against the inclined wall of the passage 19 in the piston 5, a vacuum will be created in the cylinder 4 when the piston 5 is moving toward the left and grease will be drawn into the cylinder 4. When the pistons 3 and 5 have moved to the extreme left hand position as shown in the drawing, the handle 8 is turned to bring the upper passage 41 in the piston

40 into communication with the passages 43 and 23, at which time air under pressure will be admitted to the cylinder 2 at the left hand side of the piston 3, which will cause 5 the pistons 3 and 5 to move toward the right. As the pistons 3 and 5 move toward the right, grease will be forced through the passage 19 in the piston 5, whereupon the ball 20 will be raised from its seat and the grease 10 will flow from the passage 19 into the cylinder 37 at the left of the piston 5. Upon the second left hand movement of the pistons 3 and 5, the grease in the cylinder 37 will be forced into the passage 39 and pressure 15 exerted against the piston 12 will move the same to the left against the action of the spring 16 until the transverse passage 18 in the piston 12 will be moved to communicate with the enlarged opening in the passage 20 39, whereupon the grease will be forced from the passage 39 into the part to be lubricated. As the pistons 3 and 5 again move to the right, the piston 12 will also move to the right to abut against the stop 25 15 and a vacuum will be created in the cylinder 37 upon such movement of the pistons and the right hand movement of the piston 12 will at that time relieve the pressure created in the connections between the nipple 30 38 and the part to be lubricated so that this connection can be broken and another connection made with the part to be lubricated without the inconvenience and annoyance of having grease escape from the connecting member due to the previous pressure 35 built up therein. It will thus be seen that each left hand movement of the pistons 3 and 5 draws a quantity of grease into the cylinder 4 and each right hand movement 40 of these pistons will transfer the major portion of the grease from the cylinder 4 to the cylinder 37 and each subsequent left hand movement of the pistons will force the grease from the cylinder 37 to the part to 45 be lubricated.

It will be understood that changes may be made in the specified invention described, such as substitutions of equivalents, without departing from the spirit of functions of 50 the invention, the scope of which is commensurate with the appended claims.

Having thus fully described the invention, what I claim as new and desire to secure by Letters Patent is:

55 1. A device of the class described comprising a casing having three cylinders, two of which being of substantially the same bore and the third being of a large bore; interconnected pistons reciprocable in said cylinders; means for admitting fluid under pressure to either side of said larger piston and simultaneously relieving fluid pressure from the opposite side thereof to reciprocate said piston; means for admitting viscous lu-

bricant into one of said smaller cylinders; 65 a longitudinal passageway in said smaller piston; valvular means in said passageway to allow the lubricant to pass therethrough in discharge direction only; an outlet in said casing whereby lubricant is discharged from 70 said device; valvular means in said passageway whereby pressure is automatically relieved in said outlet passage; and means to limit the movement of said last-named valvular means. 75

2. A device of the class described comprising a casing provided with three cylinders, two of which being of substantially the same bore, and the third being of a larger bore; interconnected pistons reciprocable in said cylinders; means for admitting fluid under pressure to either side of said larger piston and means for simultaneously relieving pressure from the opposite side; a passage way thru said smaller pistons, a check valve therein whereby grease is forced in one direction only therethru; and a discharge outlet connected with the chamber into which the grease is to be introduced. 85

3. In a grease gun, a large piston, smaller pistons secured to said larger piston and projecting axially therefrom in both directions, a casing providing cylinders for said pistons, an axial passageway extending 95 from the face of one of said smaller pistons to the face of the other, means for connecting one of said smaller cylinders with a source of grease supply, means for connecting the other of said smaller cylinders with a point of deposit, means for automatically relieving pressure in the last named means upon movement of said pistons in one direction, and means for admitting a fluid under pressure to either side of said large piston and simultaneously relieving pressure on the other side thereof to operate said pistons. 100

4. A grease gun comprising a casing provided with three cylinders, one of which is 110 larger than the other two, a single piston member reciprocable in said smaller cylinders, a piston for said large cylinder mounted on said first named piston intermediate its ends, a discharge opening leading from one of the smaller cylinders, a check valve in said opening, an inlet leading to the other of said smaller cylinders, a passageway leading from one of said smaller cylinders to the other thereof, a check valve in said passageway, and means for admitting fluid pressure to either side of said larger piston and simultaneously relieving fluid pressure from the other side thereof to operate 115 said pistons. 120

Signed by me at Detroit, Michigan, this 13th day of July, 1921.

GUY MYERS HARTSOCK.
